[57] CLAIM

The ornamental design for a holder tray for game pieces or the like, as shown and described.

DESCRIPTION

FIG. 1 is a perspective view of a holder tray for game pieces showing my new design;

FIG. 2 is a top plan view thereof;

FIG. 3 is a front elevational view, the rear elevational view being substantially a mirror image thereof;

FIG. 4 is a bottom plan view thereof; and

FIG. 5 is a left side elevational view, the opposite side elevational view being substantially a mirror image thereof.
